SAFETY CLOSURE FOR CONTAINERS

Eugene Holt, North Hollywood, Calif., assignor to
Safety Precisions Limited, Montreal, Quebec,
Canada, a company of Canada

Application July 1, 1950, Serial No. 171,721

2 Claims. (Cl. 222—543)

1

This invention relates to closures for bottles and other containers, its object being to provide an improved construction which, while allowing adequate access to and egress of the contents of the container, cannot be completely removed therefrom or readily or inadvertently released or opened by children by reason of the degree of physical effort and skill required to operate it, which effort and skill would not normally be within the capabilities of a child.

According to the present invention the improved closure for bottles and other containers comprises an annular outer member at the upper part of the container, said outer member having a shoulder of reduced diameter and serving to define an outlet opening for the container, a U-shaped inner member slidably arranged therein in inverted position with the free ends of its arms within the container, the distance between the tips of the arms being greater than the diameter of the reduced shoulder of the outer member whereby the inner member is prevented from becoming completely removed from the container by contact of the tips of the arms with the shoulder, and a sprung press-cap inseparably connected to the inner member and adapted to grip onto the exterior of the outer member when said press-cap is placed over the outer member and snapped into closed position.

The arms of the inner member may have, at their tips, outwardly extended portions the outer ends of which are a greater distance apart than the diameter of the shoulder so as thereby to contact the shoulder and prevent complete removal of the inner member.

An embodiment of the invention is shown by way of example in the accompanying drawing which is a central vertical section of a container having a closure shown in open position.

In this drawing, a cylindrical container 53 has at its upper part a shoulder 56 of reduced diameter. 55 is an inverted U-shaped inner member having at the tips of its arms outwardly extending portions 55¹ which engage as shown beneath the shoulder 56 so as to prevent complete withdrawal of the inner member 55 from the container. At the upper central portion of the inner member there is secured, by a rivet 55², a sprung press-cap 54 of the well-known kind consisting of a central dished portion 57 having a depending peripheral flange consisting of segments 58. The position of the press-cap shown is one of its two stable positions. If the segments 58 of the flange are pressed radially inwards, the dished portion 57 is snapped into a domed shape with consequent inward movement of the free ends of the segments 58. If the press-cap and inner member are first moved fully inwardly, the above-described action takes place and the segments engage into the corresponding exterior contour of the shoulder 56.

2

I claim:

1. A closure for bottles and other containers comprising an annular outer member at the upper part of the container, said outer member having a shoulder of reduced diameter, and serving to define an outlet opening for the container, a U-shaped inner member slidably arranged therein in inverted position with the free ends of its arms within the container, the distance between the tips of the arms being greater than the diameter of the reduced shoulder of the outer member whereby the inner member is prevented from becoming completely removed from the container by contact of the tips of the arms with the shoulder, and a sprung press-cap inseparably connected to the inner member and adapted to grip onto the exterior of the outer member when said press-cap is placed over the outer member and snapped into closed position.

2. A closure for bottles and other containers comprising an annular outer member at the upper part of the container, said outer member having a shoulder of reduced diameter and serving to define an outlet opening for the container, a U-shaped inner member slidably arranged therein in inverted position with the free ends of its arms within the container, outwardly extended portions at the tips of the arms of the inner member, the outer ends of the outwardly extended portions being a greater distance apart than the diameter of the shoulder of the outer member whereby the inner member is prevented from becoming completely removed from the container by contact of the outwardly extended portions with the shoulder, and a sprung press-cap inseparably connected to the inner member and adapted to grip onto the exterior of the outer member when said press-cap is placed over the outer member and snapped into closed position.

EUGENE HOLT.
